(57) **CLAIM**

The ornamental design for a trapezoidal hook, as shown and described.

DESCRIPTION

FIG. 1 is an isometric view of a trapezoidal hook;
FIG. 2 is a front elevation view thereof; the rear elevation view being a mirror image thereof;
FIG. 3 is a left elevation view thereof;
FIG. 4 is a right elevation view thereof;
FIG. 5 is a top elevation view thereof; and,
FIG. 6 is a bottom elevation view thereof.
The broken lines shown in the drawings illustrate portions of the trapezoidal hook that form no part of the claimed design.
